UNITED STATES PATENT OFFICE.

NICKOLAS B. IPPOLITO, OF PITTSBURG, PENNSYLVANIA.

SAFETY-LAMP.

No. 909,416.

Specification of Letters Patent.

Patented Jan. 12, 1909.

Application filed October 17, 1903. Serial No. 458,190.

To all whom it may concern:

Be it known that I, NICKOLAS B. IPPOLITO, of Pittsburg, in the county of Allegheny and State of Pennsylvania, have invented 5 certain new and useful Improvements in Safety-Lamps, of which the following is a specification.

My invention relates to safety-lamps and the prime object of the present invention is 10 to provide a new and improved non-explosive oil-lamp.

In the accompanying drawing, which illustrates applications of my invention, Figure 1, is a broken view of a lamp embodying my invention shown partly in elevation and partly in section; Fig. 2, a detail cross-section taken on line II-II of Fig. 1; Fig. 3, a part elevational and a part sectional view of a modified form; Figs. 4 and 20 5, detail sectional views of the form of collar or ring-member employed in the form of Fig. 3; and Fig. 6, a detail plan partly in section of the ring-member, the section being taken on line VI-VI of Fig. 5.

Referring to the drawing, the lamp as illustrated comprises a fluid containing font 1 made of glass and formed with a neck 2. The font 1, however, may be made of metal as I do not desire to limit myself to a glass- 30 lamp.

3 designates a burner adapted to be secured to a collar or ring-member 4. Ring-member 4 is adapted to be secured to the neck 2 of the font in the usual manner and 35 comprises an annular seat 5 arranged within the neck and an outer depending flange 6 arranged on the outside of the neck, as shown, the ring-member is secured to the neck by some suitable plastic material as indicated at 7. In the form of Fig. 1, seat 5 is threaded and is adapted to receive a threaded portion of a burner-flange 8. In the form of Fig. 3, I provide the seat with bayonet-slots 9, and the burner-flange 8 45 with nibs or projections 10, the latter being adapted to enter the said bayonet-slots 9.

Extending downwardly from the neck to within a short distance from the bottom of the font I provide a tube or cylinder 11. 50 Tube 11 is open at its upper end and closed at its bottom and is formed with a series of small upwardly inclined openings 12. In the form of Fig. 1, the upper end of the tube is directly secured to the burner and 55 in this form I provide a detachable cap 13 for closing the lower end of the tube. As

shown the cap 13 is externally threaded and the lower portion of the tube is internally threaded to engage the threads of the cap. A wire gauze 14 surrounds the tube and 60 covers the small openings thereof.

Adjustably secured to the burner and extending downwardly into tube 11 is a wick 15. To properly deliver the oil or other lighting fluid, from the font to the burner 65 and to insure a complete consumption thereof, while maintaining a good flame, I provide an absorbent filling or packing 16 placed within the tube and arranged in contact with or in capillary communication 70 with the wick. In practice, the absorbent filling in the form of Fig. 1, is placed within the tube by removing the detachable cap 13 on the lower end of the tube and forcing 75 said filling up into the tube on both sides of the wick.

In the form of Fig. 3, the tube is secured to the ring-member instead of the burner as in the form of Fig. 1, and in this form, the absorbent filling may be introduced 80 through the upper open end of the tube.

What I claim is:

1. In a lamp having a fluid containing font, the combination with a burner, of a tube in the font having a closed lower end 85 and open at its top, and formed with a series of small openings, a wick in the tube, an absorbent filling in the tube in contact with the wick, and a wire gauze surrounding the tube and covering the small open- 90 ings.

2. In a non-explosive oil-lamp having a fluid containing font, the combination with a burner, of a tube extending downwardly 95 into the font having a closed lower end and open at its top and formed with a series of small upwardly inclined openings, a wick in the tube, an absorbent filling in the tube in capillary communication with the wick, 100 and a wire gauze surrounding the tube and covering the small openings.

3. In a safety-lamp having a fluid containing font, the combination with a burner, of a tube secured to the burner and extending downwardly into the font, said tube 105 open at its upper end and closed at its lower end and formed with a series of small openings, a wick secured to the burner and extending downwardly into the tube, an absorbent filling in the tube in contact with 110 the wick, and a wire gauze surrounding the tube and covering the small openings.

4. In a safety-lamp having a fluid containing font, the combination with a burner, of a tube secured to the burner and extending downwardly into the font, said tube 5 open at its upper end and formed with a series of small openings, a detachable cap for closing the lower end of the tube, a wick secured to the burner and extending into the tube, an absorbent filling in the tube in contact with the wick, and a wire gauze surrounding the tube and covering the small openings.
5. In a safety-lamp having a fluid containing font provided with a neck, the combination of a ring-member having a burner-seat within the neck and a depending flange 75 on the outside of the neck, of a burner, a
- tube secured to the burner and extending downwardly into the font, said tube open at its top and formed with a series of small 20 upwardly inclined openings, a detachable cap for closing the lower end of the tube, a wick secured to the burner and extending into the tube, an absorbent filling in the tube in capillary communication with the 25 wick, and a wire gauze surrounding the tube and covering the small openings.

In testimony whereof I affix my signature in presence of two witnesses.

NICKOLAS B. IPPOLITO.
